Application December 29, 1943, Serial No. 516,106
In Great Britain May 13, 1938

3 Claims. (Cl. 250—17)

1

This invention relates to radio transmission systems.

Systems of radio communication have inherent limitations as to the speed and/or quality of the transmission of intelligence by reason of their inability beyond a limit to produce and radiate high frequency signals, which, when received, can be resolved into satisfactory reproduction of the desired original signals. One limitation arises by reason of the uneven frequency response of the tuned circuits in the transmitter. Means such as overcoupling may be employed whereby improvements in the above respects can be achieved when the wavelength is a few hundred metres. The defect however is difficult to eliminate or even reduce on the shorter wavelengths of say below 50 metres, especially in transmitters which are arranged for operation on several different wavelengths.

The present invention provides a method by which the defect above referred to may be considerably reduced in a transmitter so that the speed or quality or both of the transmission may be improved to a degree where it is substantially limited only by the receiving means which are employed for the transmitted signals. Since the performance of the receiver can be improved relatively cheaply, the present invention provides, *inter alia*, a saving in the cost of the system.

The present invention is concerned not so much with improving the performance of transmitters modulated with relatively complex signals such as sound or vision modulation proper, but relates more particularly, although not exclusively to systems using instantaneous changes of carrier level, such as the "marking and spacing" of code and the impulses used in television for synchronisation.

The problem with which the present invention deals is as follows. When an attempt is made to excite a resonant circuit in conformation with a signal element of rectangular wave form such as is required in the systems mentioned in the preceding paragraph, the resulting response in the circuit is modified in a manner dependent on the resistance and capacity in the circuit. It is convenient to consider the case where a circuit having resistance R and capacity C is required to respond to a rapid succession of dots, that is square topped envelopes recurring at relatively high frequency. As is well known, the level of the first part of the dot will cause the radio frequency current to build up exponentially in the circuit asymptotically to the "mark" level whilst the end of the signal will initiate an exponential fall

2

to the "space" level which is usually zero. The time taken for the current to rise or fall to a reasonable percentage of the final value is dependent on the time constant RC of the circuit.

5 If this time is comparable with the duration of either mark or space required in say high speed signalling, considerable distortion of the wave form results.

In short wave transmission the value of C is frequently irreducible below the internal capacity of the power valves employed. Similarly these valves for efficient operation require a certain minimum value of R determined by the electrical characteristics of the valves. Thus the time constant RC is more or less fixed in value on those transmitters which are the best suited for high speed operation.

The case under consideration is similar to that involved in "picture" modulation in television transmission. Indeed the latter, which is normally considered as a complex wave form containing all frequencies from zero (direct current) up to the limit frequency of the system (a few megacycles) might in the ideal embodiment comprise a succession of horizontal "steps" occurring at various levels in accordance with the brightness of successive picture elements joined by verticals, the length of the steps corresponding with the size of the picture element as is predetermined in the system. In practice this condition is not fulfilled nor with the existing limitations is it necessary, for since by analysis the "stepped" wave must cover an infinite frequency spectrum, the method would not be practicable. At present the

30 upper limit of frequencies transmitted is between two and three megacycles. In order to achieve even this performance however, it is found necessary to reduce the effective value of R in the tuned circuits of the transmitter to a value far

40 below the optimum from a point of view of the valve characteristics, with consequent poor efficiency. Thus it is found that in a transmitter requiring a frequency response flat within three decibels over a band of 1.5 megacycles the conversion efficiency is less than 15%: 60 kw. input being necessary to obtain 7.5 kw. output at 50 megacycles carrier frequency: see Conklin and Gihring, "Television transmitters," R. C. A. Review, July 1937.

45 50 The rectangular wave forms now under consideration constitute, as mentioned above, a parallel or similar case with the foregoing and the object of the present invention is to provide a satisfactory output wave form with relatively great efficiency.

The present invention provides a simple method by which the above defects are at least materially reduced but without sacrifice of efficiency by a particular corrective predistortion of the signal before it is applied to the transmitter proper. The nature of the invention will be the better understood by reference to the accompanying drawings in which Figs. 1 and 2 are diagrams illustrating the problem involved and its solution according to the invention, Fig. 3 is a diagram indicating how the invention is carried out, and Fig. 4 is a diagram illustrating a keying arrangement providing impulses.

Referring to the drawings at 1 is shown the required ideal rectangular wave form of a signal which it is desired shall be transmitted. The curves 2 and 3 illustrate the actual response of a turned circuit when a signal 1 is applied thereto, these two curves being of general exponential form. It may be assumed that in the example shown the value of the time constant RC of the circuit is of the same order as the duration of the "marking" period. That is to say, the response will have risen or fallen to $1/e$, namely, to about 63.2% of the value to which it is tending in a time comparable with the length of the signal.

It will be appreciated that the respective forms of the curves 2 and 3 result in different effects on the transmission. In the case of curve 2, the shorter the signal duration t , the lower will be the maximum response to it, the form of curves 2 and 3 being independent of the signal duration, whilst curve 3 indicates a persistence of the signal in a manner which will seriously interfere when a succeeding signal is spaced an economically small period of time from the preceding signal. It is with reference to curve 3 that the present invention operates with particular advantage.

Since the form of curves 2 and 3 is fixed, it is clearly not practicable so to predistort the signal that the resulting response is one of perfectly rectangular wave form. As hereinbefore explained, however, the rate of rise or fall of current in the circuit is dependent on its time constant and the final value to which the current tends. The time constant being fixed, the predistortion necessary to improve the output wave form must have reference to the asymptotic values of current.

In Fig. 2 wherein curves 1, 2 and 3 are repeated, there is shown added the portions 4 and 5 to the signal before it is applied to the transmitter. Initially the response will follow an exponential curve which would, for a given time, attain the same fraction of the asymptotic value 6 as the curve 2 of the maximum value of curve 1. Thus the rise will follow the new curve 8 for the duration of the added portion 4. If the latter is maintained until the curve 8 has met the level 4 the response will have been improved by the amount bounded by the curves 4, 2 and 8, this area being shown shaded. The increase in the level 6 will enlarge this area, the final limitation being the slope of the exponential curves at their starting points. This slope will be the same for all curves, it will not be infinite and it will have a value dependent on the resistance in the circuit.

Similarly at the end of the signal the response will be improved by the addition 5, the portions 9 and 10 corresponding with the portions 4 and 8 in the first instance. In general the transmitted high frequency level will be required to be at or near zero immediately after a signal element has been radiated. Considering therefore the line 75

11 to represent zero value of high frequency it will be seen that the added portion 5 must be below zero, that is of negative sign. This is obtained, according to the present invention, by 5 reversing the phase of the generated high frequency at the point 12.

Referring to Fig. 3, this shows a source 21 of high frequency energy such as a frequency controlled oscillator. The source 21 produces a voltage wave across the conductors 22 and 23 which is symmetrical about the potential of the lead 24 which may be earthed. At 25 and 26 are shown a pair of modulating devices of well known or convenient type. Each such device may be a grid modulated radio frequency amplifier, the amplification of the valve varying with the grid bias which is supplied to the lead 27 or 28. The device 25 is fed with high frequency energy from the conductors 22 and 24 whilst the device 26 is fed from the conductors 23 and 24. The amounts of energy passed on by the devices 25 and 26 are controlled by the potentials of the modulation leads 27 and 28, respectively, with regard to the common connection 24a. Thus the devices 25 and 26 may be said to operate in push-pull or anti-phase: their outputs will be in 180° phase relation. Their output connections, however, instead of being also connected in push-pull relation are connected in parallel so that with either of the devices 25 or 26 inoperative, the other will pass carrier frequency energy to the output leads 31 and 24 whence it passes to an amplifier 32 which raises the energy to any desired level before feeding it to the aerial or other load.

It will thus be seen that by suitable manipulation of the potentials on the leads 27 and 28 with respect to the lead 24a, carrier energy of either in-phase relationship with the carrier passing the conductors 22 and 24, or in antiphase relation therewith may be fed into the amplifier 32. The potentials of the leads 27 and 28 with relation to the lead 24a are regulated by the signal controlling device 29 which itself receives the original signals on the input terminals 33 to which may be connected a mechanical key or other equivalent signal source.

Supposing, for example, that the leads 27 and 28 are effectively the grid bias connections to the valves used in the amplifier modulators 25 and 50 26 and that in the absence of a signal both grids are held at sufficiently negative potential with respect to earth so that both devices 25 and 26 are "shut off," the operation of the apparatus 45 when a signal element is applied to the terminals 33 is as follows:

The arrival of the front of the signal element will operate on a combination of discharge tubes, resistances and capacities so as to produce between the leads 27 and 24a a higher and if required steeper wave-front than that of the initiating wave, which steeper wave then falls after a predetermined time, as indicated at 4 in Fig. 2. The actual potential of the lead 27 at any instant will depend on the modulation characteristic of the device 25 and in general the latter may be "shut off" to any desired extent. Thus the level 11, Fig. 2, as far as the front of the signal element is concerned may be at a large negative value. At the end of the initiating signal the lead 27 will be returned to this negative value whilst simultaneously the lead 8 applies to the device 26 a similar impulse to that initially given by the lead 27 to the device 25, this releasing a burst of anti-phase high frequency energy to the leads 24 and 31. This will have the effect of reduc-

ing in the aerial the tailing portion 3 (Fig. 2) as hereinbefore described. This anti-phase burst must be so controlled that its energy is substantially wholly and solely utilised in augmenting the rate of decrease of the in-phase signal. It is of course undesirable that any of such anti-phase modulation should actually appear in the aerial.

It will be appreciated that the important parts of the additional impulses inserted by the device 29 (Fig. 3) are firstly the steepness of the impulse fronts and secondly the effective amplitudes thereof. In the example given the impulses are narrow rectangular ones, but apart from the two characteristics mentioned above the impulses need not conform to this shape. In fact any impulses having steeper wave fronts and higher initial amplitude than that produced by the signal alone will clearly effect an improvement. The particular circuit combinations used to provide the distortion may thus be of simpler form than that required for generating the narrow wave shape shown.

In many cases the correction afforded by the first impulse may be unnecessary whilst on the other hand the spacing of successive signals will render the second or anti-phase impulse desirable.

It will be appreciated that the advantage of the system above set forth and described is the improved degree of accuracy of transmission obtainable. Moreover, with normal systems of keeping, wherein the "spaced" condition is obtained by "shutting off" a valve by applying a large negative potential to its grid, for example, the residual interelectrode capacities of the valve or valves may still permit a small amount of energy to pass through them continuously. A further advantage, therefore, of the system lies in the fact that during the "space" condition both of the modulators 25 and 26 will pass such energy and their inputs being anti-phase but their outputs in parallel, no energy of carrier frequency will pass to the final amplifier.

The use of the first impulse, however, presupposes that the transmitter is capable, at least for a very short time, of producing considerably more power than is required for the normal "mark" level. In some cases this may not be considered economical, although it may prove desirable to employ amplifiers which will give this condition in all the stages except the output stage. Some improvement will result from this arrangement.

It will be appreciated that the distorting device 29 must be arranged for the generation of impulses. In general, it may comprise a pair of impulse generators of which the output of one is connected between the leads 27 and 24a, whilst the output of the other is connected between the leads 28 and 24a. These generators may for example be of the type utilising switches such as grid-controlled discharge tubes and provided with suitable resistance-capacity circuits to generate when switched or "triggered," impulses of the required form. These two generators are so arranged that the first is triggered by the rising front of the signal element which is applied to the terminals 33, after which the signal element, with the impulse added to it is passed to the leads 27 and 24a, whilst the wave-front produced by the end of the signal element may be used to trigger the other impulse generator which thus produces a similar impulse on the leads 28 and 24a. Fig. 4 illustrates diagrammatically an arrangement for producing the impulses.

Referring to Fig. 4 which is to be considered in conjunction with Fig. 3, the conductors 28 and 24a of the latter diagram have connected across them the resistance R1 which is of low value and the conductors 27 and 24a have connected across them the resistance R2.

Associated with the conductors 27 and 28 is a quick-acting switch or relay S of the two-pole type arranged so that when one of its poles or blades is closed the other is open. The terminals x and y of the switch blades are adapted to be connected to a source of voltage V through a combination of resistances and condensers as follows. The switch terminal x is adapted to be connected to the source V through the resistance R3 which is bridged by a condenser C2, whilst the terminal y of the switch S is adapted to be connected to the source V through the resistance R4 which is high compared with R1, the latter being bridged by the condenser C1. It is assumed that the switch S is operated electromagnetically by means of a coil s' connected to the terminals 33 (Fig. 3) to which an electro-mechanical keying arrangement is connected. The arrangement shown in Fig. 4 operates as follows.

When no voltage is applied to the terminals 33, the coil s' is de-energised and the switch S occupies the position shown so that in the steady condition the resistances R4 and R1 act as a potential divider for the lead 28 across the source V. Therefore, since the value R1 is low compared with that of R4, the voltage on the lead 28 is near zero whilst the condenser C2 having been discharged by the resistance R3, the potential of the switch terminal x is that of the source V. When the voltage is applied to terminals 33, the switch blades move over to the other position so that the potential of x appears on the conductor 27. However, owing to the condenser resistance combination C2R3 the voltage on the conductor 27 drops exponentially to a steady level which will be

$$\frac{R_2}{R_3 + R_2} \cdot V$$

During this time the condenser C1 is no longer bridged by the low resistance R1 and so it charges up to the potential V through the resistance R4. When the voltage is removed from the terminals 33 the switch S rapidly moves over so that the potential of the conductor 27 falls immediately to zero by reason of the resistance R2, but the potential V on the condenser C1 momentarily appears on conductor 28, this potential falling exponentially to zero as the condenser C1 discharges through the resistance R1.

We claim:

1. A radio transmission system arranged to transmit rapid changes in carrier level, means to produce an in-phase modulated carrier, means to produce an anti-phase modulated carrier, means controlling the in-phase and anti-phase carriers and arranged upon a rapid decrease in input signal to supply said anti-phase carrier producing means with an initial impulse whereby the anti-phase carrier solely augments the rate of decrease of the in-phase carrier level.

2. A radio transmission system arranged to transmit rapid changes in carrier level, an aerial, means to produce an in-phase modulated carrier, means to produce an anti-phase modulator carrier, means controlling the in-phase and anti-phase carriers and responsive to a rapid increase in input signal to superimpose thereon an initial impulse to augment the rate of increase in car-

rier level in the aerial, said last-named means being effective upon a rapid decrease in input signal to supply said anti-phase carrier producing means with an initial impulse to solely augment the rate of decrease of the in-phase carrier level.

3. A radio transmission system as claimed in claim 2, wherein the means controlling the in-phase and anti-phase carriers is adjusted to cause the anti-phase carrier producing means to bring down the carrier level in the aerial rapidly to substantially zero.
